UNITED STATES PATENT OFFICE.

HENRY STEWART, OF PROPHETSTOWN, ILLINOIS.

BOX-FORMING MACHINE.

SPECIFICATION forming part of Letters Patent No. 606,692, dated July 5, 1898.

Application filed November 16, 1896. Serial No. 612,388. (No model.)

To all whom it may concern:

Be it known that I, HENRY STEWART, a citizen of the United States, residing at Prophetstown, county of Whiteside, and State of Illinois, have invented certain new and useful Improvements in Box-Forming Machines, of which the following is a full, clear, and exact description, reference being had to the accompanying drawings and to letters and figures of reference marked thereon.

My invention relates to a machine for forming boxes from previously-prepared blanks of wood or other material, and has for its object to accomplish all of this and to secure other and further advantages in the matter of construction, adjustment, and operation and to provide a machine which may be easily and quickly manipulated, entirely or in part automatic, and capable of being operated with great rapidity.

My improvements involve certain new and useful arrangements or combination of parts and peculiarities of construction, as will be herein first fully described, and then pointed out in the claims.

To give a more clear and better understanding of my invention, I will first describe the peculiar construction of the box which the machine puts together and then the machine.

The four sides of the box are prepared in one long continuous strip, having at proper intervals transverse V-shaped grooves cut nearly through the stock in such a manner that when the remaining stock is made tough by moistening it will bend and when bent to right angles the side faces of the V-shaped grooves will meet and form miter-corners for three of the corners of a box, the fourth corner being formed by grooving each end of the side blank in such a way as when they meet and are driven together they form a locking-corner. In proper position for the reception of the bottom blanks the side blanks are usually longitudinally grooved and the bottom blanks properly prepared for being folded into said grooves. Glue may also be applied in the miter and locking corner joints in such a way as when properly prepared and put together to form a strong, neat, and substantial box. The operation then of forming boxes from previously-prepared parts is simply to apply glue to the miter and locking corners

and properly wrap the side blanks around the bottom blanks and force the locking-corner ends of the side blanks together. This is substantially what my machine does automatically.

In the accompanying drawings, forming part of this specification, Figure 1 is a front elevation of my machine with a portion of the frame broken away to show the position of the auxiliary frames B and C. Fig. 2 is a sectional side view as divided on the line xx , Fig. 1. Besides the working parts it shows a number of side and bottom blanks in position in their respective magazines. Figs. 3, 4, 5, 6, 7, 8, and 9 are detail views of the forming-head, of which Fig. 3 is a side elevation with one of the circular faces k^{18} removed and a portion of the front parts of k^{17} and k^{10} broken away. One of the forming-clappers is seen in position ready for duty, the other in the position it assumes when a box is folded. Fig. 4 is one of the forming-clappers in a forming-clapper frame and shows the screw used in adjustment. Figs. 5, 6, and 7 are detail views of parts which are seen in Fig. 2 and show the method of procuring the circular adjustment. Fig. 8 is an end and Fig. 9 a side view of the part in which the swivel ends of the screws which adjust the forming-clapper frames are fitted. Its position is in the crotch of the inside circular part of the forming-head. Fig. 10 is a perspective view of the auxiliary frames B and C, showing the relation one with the other and the screws for adjusting them. Figs. 11 and 12 show the circular or tilting adjustment of the magazine for bottom blanks. Fig. 11 is a side elevation of the bottom magazine turned bottom upward. Fig. 12 is a perspective view of one of the circular openings in which the circular parts from the bottom magazine fit. Figs. 13 and 14 are detail views of the clenching-block and show the means of tilting the clenching-groove of the clenching-block. Fig. 15 is a perspective view showing the glue-tank partially removed from the steam-jacket. A section of the steam-jacket is broken away to show its construction. Fig. 16 is a plan view of the bottom of the magazine for side blanks. Fig. 17 shows one of the slides shown in Fig. 16. Fig. 18 is a side view in perspective of one section of a glue-brush wheel with brushes removed. Fig. 19

is a side elevation of the same with brushes in place. Fig. 20 is a view of a plunger for side blanks. Fig. 21 is a section in perspective of the cross-piece A². Fig. 22 shows a 5 trip-slide which fits in the groove shown in Fig. 1 underneath the guide projection from the plunger J. Fig. 23 is a plan view of the end stop of the magazine for side blanks. Fig. 24 is a perspective view of the front of 10 the magazine for side blanks. Fig. 25 shows the eye-headed bolt d¹³. Fig. 26 shows a crank-shaft that reciprocates the plunger J and the ratchet e'. Figs. 28 and 29 are perspective views of the forming-block and the forming-block frame. Figs. 30, 31, 32, and 33 are 15 detailed views of the plunger for bottom blanks, of which Fig. 30 is a view of the face side, the bottom part of g' being broken away to show the adjusting-screw. Fig. 31 is a view of one 20 edge; Fig. 32, a view of the inside movable frame, and Fig. 33 a perspective of the circular or tilting adjustment part. Fig. 34 is a figure designed to show the variation in position between a square and an oblong rectangular box when formed in my machine. Fig. 35 is an elevation of a side blank of a box.

A framework is provided to support the working parts of any suitable design or material, but preferably, as in this design, of 25 cast metal, of which A A A A is the main frame, cast in sections and securely fastened together. For additional strength and to be of support for some of the working parts the cross-pieces A' A² are embodied in the main 30 frame. Also as supports for the bearings of different journals the brackets a a a a are embodied in the framework. In this framework, with a little modification, especially for the manufacture of any particular-sized box, 35 all the working parts may be directly embodied; but for convenience of adjustment and to adapt it for forming different-sized boxes the auxiliary frame B is provided and also the auxiliary frame C, both of which 40 support important parts and with other adjustments will be more fully explained hereinafter.

In the upper part of the machine, at D, is the magazine for the reception of the side 45 blanks, in which are to be piled the side blanks, one upon the other, with their grooves downward, their edges, which are to enwrap the bottom blanks, forward, and the center V-shaped groove in line with the apex of the forming-block.

To form the magazine D, I use here the bottom plate d⁵, the back piece d, which is fastened permanently in the frame of the machine and has an opening between it and 50 the bottom plate sufficient for the reciprocating of the plunger J, the adjustable magazine-front D', Figs. 24 and 25, and the end stop, Fig. 23.

The magazine-front D' is hung suspended 55 in guides from the top of the main frame by means of the screws d⁸ d⁸, which fit in corresponding threads in the cross-piece d¹. By

means of these screws the opening between the magazine-front and the bottom plate d⁵ can be adjusted to admit of the passage of 70 one and but one side blank at a time. The horizontal projections d⁹ d⁹ are guides to prevent the side blanks riding the plunger as they pass from the magazine.

The plate d¹⁰ is adjustable to correspond 75 with the width of the side blanks by means of the horizontal projections d¹¹ and d¹². d¹¹ passes through d⁷ and is fastened in any position by the eye-headed bolt d¹³, through the eye of which d¹¹ passes. d¹¹ is fastened by 80 tightening the nut d¹⁴. The projection d¹² has a double office—first, to prevent the lopping of one end of the plate d¹⁰, and thus conflict with the reciprocating of the plunger J, which without some precaution would be liable to 85 occur, and, second, to prevent the side blanks riding the plunger J.

d³ is an end stop capable of longitudinal adjustment by means of the bent shaft d¹, which passes through the frame and is fastened at any position, according to the length 90 of the side blanks.

The bottom of the magazine d⁵ is provided with openings through which pass the glue-brushes, and to afford adjustment for the different positions of the glue-brushes for different work d⁵ is provided with cross-sections d⁶, which may be slid backward and forward in slots provided for the same as the work may require. Immediately underneath this 95 magazine is the glue-magazine E, which is a plain tank made of sheet-copper or any suitable material. Through this, fitted in suitable bearings, passes the shaft e. On this 100 shaft at proper intervals (which are changeable) are the brush-wheels e' for gluing the different corners of the boxes. These are revolved with ratchet and pawl e², which is reciprocated with a crank e³ through the connecting-rod e⁴.

Figs. 18 and 19 are sectional views of one of the brush-wheels, showing in Fig. 19 the brushes in position. It consists of two disks, one or both of which are grooved for the reception of the brushes e⁵, which are common glue-brushes. When the brushes are placed in position and the two disks clamped together, they become as spokes in a hub. The reason for placing them at intervals and the use of the ratchet is apparent when it is considered that in sliding-cover boxes the side blanks have a groove in which the cover slides, and if this groove be filled with glue it would conflict with the passage of the cover. It is also apparent that as the crank e³ is driven by an extension of the crank-pin j³ it may be set so as to make the turn of the shaft e at exact intervals and can bring up a set of brushes as the side blank is leaving the machine to do the work of applying glue to the 110 various corner-joints and pass down out of the way just before the groove or the sliding cover is reached.

Underneath the two receptacles just de-

scribed is a third receptacle for the bottom blanks, which will be known hereinafter as the "bottom magazine" F. It consists of a V-shaped trough or rack having at its bottom the longitudinal groove or opening f'. Also near each end the pulleys f² f³, in which and around which passes the cord f⁸, which has at one extremity the weight f⁴, at the other the handle f⁵, and at proper position midway is fastened to the follower f⁶. In this magazine are placed the prepared bottom blanks, resting upon one corner and having their faces which are to be bottommost in the boxes facing the front of the machine. The office of the follower is to provide a pressure against the bottoms to force them forward as they are fed out by the bottom plunger.

The bottom plunger G reciprocates in guides in the main frame immediately in front of the bottom magazine. It has a recess with a V-shaped base, which in its lower position comes slightly below the V-shaped trough of the bottom magazine. This recess, being slightly shallower than the thickness of the bottom blanks, receives but one at a time. This plunger is fitted to work freely in prepared guides and is forced upward by means of the cam H on the cam-shaft H'. After the cam has passed from under the plunger it drops by its own weight, having delivered its bottom blank between the face-plate i⁵ and the bottom support M and is replenished with another bottom from the bottom magazine.

At the bottom of the magazine for side blanks is the plunger J, which is reciprocated and regulated in its throw by the pitman-rods j, which are constructed in two parts and are capable of being expanded and contracted by a right-and-left-hand threaded screw-coupling j' and the cranks j², having various crank-pin holes for the crank-pin j³. This plunger is so arranged with openings as not to conflict with the glue-brushes, the middle opening j⁴ being permanent, while the others may be adjusted to correspond with the position of the glue-brushes by sliding to the right or the left the sliding projections j⁵. To guide the plunger J, I provide the flange-like projection j⁶, which fits in the groove shown in Fig. 21. With these adjustments the plunger can be so set as with its forward movement to force the side blanks each in turn before it to such a position on the forming-block that one of its edges shall overhang the face of the forming-block a sufficient distance to receive and inclose a bottom blank. After the parts have been placed in position by their respective plungers the forming of the box is completed by the forming-head K, in conjunction with the clenching-block N.

The forming-head is reciprocated in guides in the main frame by means of the crank-wheel k on the main shaft above and the connecting-rod k'. The essential features of the forming-head are the right-angled inverted-V-shaped recess k² and the forming-clappers K' K', which hang suspended from the side

faces of the above recesses and are hinged so as to swing in a circular form. These forming-clappers have also right-angled inverted-V-shaped recesses, formed by the fork-like projections k³ k⁴. With a side blank in position it is obvious then that if the forming-head be pressed downward the side strip will be bent between the upper walls of the forming-head and the forming-block until the side walls of the center V-groove in the strip meet, and these form one of the miter-corners of the box. The other two miter-corners are formed by the forming-clappers. As these forming-clappers come in contact with the strip the projection k³, which comes in contact with the solid and unbendable portion of the strip, is forced backward, which brings k⁴ forward and bends the strip until the walls of the V-grooves meet, and also brings the two locking-corner grooved ends of the strip together below. (See Fig. 3.)

As the forming-block is a projection from the forming-block frame, which is fitted to guides in the main frame, it is capable of being depressed by the forming-head in its downward movement to force the locking-corner ends of the box together in the V-shaped recess of the clenching-block. The forming-block is then returned to its upper position by means of the weighted levers i' i'.

To provide a support that will receive the bottom blanks from the bottom plunger and retain them in position against the face-plate of the forming-block while they are being inclosed in a side blank, the bottom support M is provided with extending arms m m and the hinged base m', which is fastened to the cross-piece A'. The spring m² gives tension to the cord m³ for raising the support to allow the removal of the completed boxes. This cord may be fastened to the forming-head or connecting-rod above. When the box is formed and the bottom-support arms raised, the box is removed from the forming-block by the box-extractor L. This consists of the extending arms l', the hinged support l'', the spring l³, the cord l⁴, which is fastened to the front of the extending arms and passes underneath the hinged support to the trip l⁵. This trip may be made in various ways, but is here a strip of metal, which is fitted to reciprocate in a groove in the cross-piece of the frame and has an upper extending projection, so as to come in contact with and be forced backward by the plunger J in its backward stroke.

As it is desirable to have the V-shaped recess of the clenching-block N extend under the entire locking-corner and also not to conflict with the movements of the plunger G, the clenching-block N is fitted in the slot b. To be readily depressed by the plunger, its face is made on an incline, so as to overhang at the upper part. The clenching-block is forced forward by the spring n², and the distance forward is regulated by the screw n³, which passes through the lug n⁴.

Thus far the parts have been mostly de-

scribed without reference to adjustment, which are unnecessary for the construction of a machine to put together any particular-sized box, but which adjustments, it is readily 5 realized, are very important in a machine adapted to a variety of styles and sizes of boxes. So I have provided means of accomplishing these results and will now describe the various adjustments.

10 As two of the corners of each box formed—namely, the center miter-corner and the locking-corner—must each be in line with the center of all the V and inverted-V shaped recesses of all of these parts, (the forming-clappers excepted,) it is readily apparent that these parts must be more compactly situated for small boxes than for larger ones. To accomplish this difference in position, the auxiliary frame B, Fig. 10, is provided for raising and lowering the clenching-block and the auxiliary frame C for raising and lowering the bottom magazine. These frames are fitted by lugs b² b³ and b³ to raise and lower in guides in main frame by means of the screws B' B'. 15 These are operated, as is common in machinery, by means of bevel-gears b¹ b⁴, the shaft b⁵, and hand-wheel b⁶.

20 As the top of the bottom magazine is really formed in the frame B, it is apparent that the trough, which is described as the bottom magazine, must in order to retain its proper position raise and lower twice as fast as the frame B. Therefore the screw B' is provided with threads at its upper portion for raising the 25 frame B, measuring twice the number of threads to the inch corresponding to the lug b³ as those at the bottom corresponding to the frame C.

20 As the position of the V-shaped recess in the bottom plunger should correspond to that of the bottom magazine, the inside framework g', Fig. 30, is provided, which may be raised or lowered in the guides g² g² by the screw g³, which at its upper end is fitted to lugs in g', while the lower end corresponds to threads through the cross-piece g⁵. In the forming-head, Fig. 3, this longitudinal adjustment is provided for by hanging the forming-clappers in forming-clapper frames k⁵ k⁵, 45 these being provided with lugs k⁷, which correspond with guiding-grooves in the circular frame k¹⁰ of the forming-head. As the guiding-grooves are parallel with the respective faces of the head, it is apparent that the 50 change of position is accomplished by simply sliding the clapper-frame upward or downward. To assist in this, the screws k¹¹ k¹¹ are provided, which pass through the base of the forming-clapper frames and are hung in 55 swivels k¹² k¹². These swivels are formed by the head end of the screw k¹¹ fitting in the swivel or flange grooved slots. (Shown in Figs. 8 and 9.) This slotted part, Figs. 8 and 9, is fitted to rest in the crotch of the circular frame k¹⁰. The flanges s s, which hold this 60 part in position, occupy a similar position

above in the flange-grooves of k¹⁰ as do the lugs k⁷ of the forming-clapper frames below.

65 As referred to, two of the opposite corners of each box formed must be in line with the respective forming parts of the machine. By referring to Fig. 34 it will be seen that in a square if a line be drawn from one corner to the other the other two corners are in a horizontal line, and the angle formed by this line 70 and the sides of the square are equal; but in an oblong rectangle the other opposite corners are not in the same horizontal line and the angle 1 is greater than the angle 2. It is apparent then that the correct position of the 75 different parts is to have the side faces of their respective V or inverted-V shaped recesses tilted to correspond with the respective angles of the box. I accomplish this in all the parts in practically the same way—namely, by 80 providing an inside circular part that revolves in a corresponding circular opening in the outside part—and as the center of each circular part is the bottom of the V or the apex of the inverted V of each part it is apparent 85 that these parts can be tilted to any desired angle without changing position of the base of the V or the apex of the inverted V's of any of the parts, thus meeting the requirements. In the forming-head the circular part 90 is made in sections, the inside section k¹⁰ being larger than the outside section k¹². These parts are fastened together by screws k¹³, and each section is fitted to corresponding sections of the outside part k¹⁷, having corresponding circular openings and being fastened together with screws k¹⁶ k¹⁶. With all 95 parts in position and screws tightened the head will become as a solid head; but when loosened the inside circular parts may be 100 revolved to bring the V-shaped recess to any position required.

105 The circular adjustment of the bottom magazine is similar to that of the forming-head. The circular part f⁷ is fastened to the bottom magazine and is fitted to the circular openings f⁸ of the frame C. In the bottom plunger this adjustment consists of the circular part g, which is fitted to revolve in the circular opening of the movable frame g' and 110 may be tilted to any desired angle and fastened with the nut g⁴. In the forming-block this adjustment is found in the circular part i, which is fitted to revolve in the circular opening of the forming-block frame i'. By 115 loosening the screws i' the block may be tilted to any angle, and by tightening the screws the block is clamped rigid in any position. As it is only necessary that the face-plate i' 120 against which the bottom rests should approximate the size of the box to be formed, the forming-block consists here of a horizontal bar projection of the circular part i, against the end of which may be fastened by means of the screw i' any size face-plate that 125 may be required.

130 In the clenching-block, Figs. 13 and 14, the

circular adjustment is provided for by the circular opening of the lower part n^5 , in which is fitted the circular parts of the upper part n^6 , which has at its base a flange-like projection n^7 , which is fitted in a corresponding flange-groove in the lower part, and the upper part is fastened in position in the lower part by the countersunk set-screw n^8 .

Not previously described is the steam-jacket E' , which enwraps the glue-tank on two sides, the bottom and one end, its office being to form a support for the glue-tank and keep the glue hot therein. It is a hollow jacket made of suitable material. The side walls are shown at e^7 , Fig. 15. One end has an opening in which the glue-tank may be inserted and removed at will, and has an inlet and an outlet steam-pipe $E^4 E^4$, through which the steam passes.

The operation of the machine is quite simple. The parts are first adjusted to the size of the boxes which it is desired to form, the magazine for side blanks filled in proper position with prepared side blanks, the magazine for bottom blanks is filled with prepared bottom blanks, the glue-tank with glue in liquid form, steam is turned into the steam-jacket, and power is applied to the driving-pulley P . As power is applied direct to the crank-wheel that drives the forming-head and through positive bevel-gears to drive the other parts, it is evident that each part must do its work in exact time and when properly set will run in perfect harmony with all the other parts. The two plungers place in position around the forming-block at about the same time their respective parts of a box, the side blank having its corner grooves filled with glue as it leaves the magazine. The bottom support retains the bottom in position, the plungers recede, the clenching-block springs forward, the forming-head is driven downward, bending the center groove of the side blank to form a miter-corner, and, there being greater pressure against the forked projection k^3 than the projection k^4 of the forming-clapper, k^3 is forced backward, bringing k^4 forward and bending the other V-grooves to form miter-joints. The forming-head now comes in contact with the forming-block and forces it downward to clench the locking corner joint in the recess of the clenching-block. As the forming-head recedes the forming-block is raised by the weighted levers, the bottom support is lifted by the cord, and the completed box is removed by the extractor and all is ready to repeat the operation.

Having thus described my invention, what I claim as new, and desire Letters Patent on, is—

1. In a box-forming machine in combination with a forming-head, a forming-block, a clenching-block, magazines for the reception of side and bottom blanks, and plungers for placing the respective side and bottom blanks in position for being formed into boxes, substantially as described.

2. In a box-forming machine in combination with a forming-head, a forming-block, a clenching-block, a magazine for the reception of the bottom blanks and a plunger for feeding bottom blanks one at a time from said magazine, substantially as described. 7c

3. In a box-forming machine in combination with a forming-head, a forming-block, a clenching-block, a plunger for feeding bottom blanks one at a time from the magazine for bottom blanks, a magazine for bottom blanks, and a follower in said magazine, substantially as described. 75 80

4. In a box-forming machine in combination with a forming-head, a forming-block, a clenching-block, a plunger for feeding one at a time bottom blanks from the magazine for bottom blanks, a follower in said magazine, 85 and the means of forcing the bottom blanks forward as they are fed out of said magazine, substantially as described and for the reason set forth.

5. In a box-forming machine in combination with a forming-head, a forming-block, a clenching-block, a plunger for bottom blanks guides in which said plunger reciprocates, and a cam for raising said plunger and allowing a quick return of the same, substantially as described. 90 95

6. In a box-forming machine in combination with a forming-head, a forming-block, a clenching-block, a plunger for feeding bottom blanks from the magazine for bottom blanks, 100 a magazine for bottom blanks and means of adjusting the height of said magazine, substantially as described.

7. In a box-forming machine, in combination with a folding mechanism, a plunger for feeding bottom blanks from a magazine for bottom blanks, a magazine for bottom blanks, the circular parts f^7 which project from a magazine for bottom blanks, the circular openings f^8 , which are situated on a suitable base for the support of a bottom magazine, and means of adjusting the circular parts f^7 in the circular openings f^8 , substantially as described and for the reasons set forth. 105 110

8. In a box-forming machine in combination with a forming-head, a forming-block, a clenching-block, a bottom support, magazines for the reception of side and bottom blanks, and plungers for placing the side and bottom blanks in position to be formed into boxes, 115 120 substantially as described.

9. In a box-forming machine, in combination, a forming-head, a forming-block, a clenching-block, a support for retaining the bottom blanks against the face of the forming-block while the boxes are being formed, a magazine for side blanks, a magazine for bottom blanks, a plunger for placing side blanks in position, a plunger for placing bottom blanks in position, and an extractor for removing the completed boxes from the forming-block, substantially as described. 125 130

10. In a box-forming machine in combination, a forming-head, a forming-block, a

clenching-block, and a plunger for placing bottom blanks in position against the forming-block, substantially as described.

11. In a box-forming machine in combination, a forming-head, a forming-block, a clenching-block, a plunger for placing bottom blanks against the forming-block, a recess in said plunger for the reception of the bottom blanks one at a time, and means of adjusting 10 the vertical position of said recess, substantially as described and for the reason set forth.

12. In a box-forming machine, in combination, a forming-head, a forming-block, a clenching-block, a plunger for placing bottom blanks against the forming-block, the circular part g , of said plunger means of fitting said circular part g to said plunger, and means of adjusting said circular part substantially as described and for the reasons set 20 forth.

13. In a box-forming machine in combination a magazine and a plunger for side blanks, a magazine and a plunger for bottom blanks, a forming-head a forming-block, a clenching-block, the recess b , in which the clenching-block is fitted, the lug n^4 the screw n^5 and the spring n^6 , substantially as described and for the reasons set forth.

14. In a box-forming machine in combination with a forming-head, a forming-block, a clenching-block, a magazine for bottom blanks, a follower, a cord, and a weight, in connection with said magazine, a plunger for feeding bottom blanks from said magazine, means of reciprocating said plunger and means of retaining bottom blanks in position while being formed into boxes, substantially as described.

15. In a box-forming machine in combination, magazines for side and bottom blanks plungers for side and bottom blanks, a forming-head a forming-block, a clenching-block mounted on the auxiliary frame B, the auxiliary frame B, and means of adjusting said frame, to secure for the clenching-block a variety of vertical positions, substantially as described and for the reasons set forth.

16. In a box-forming machine in combination, a forming-head, a forming-block, a clenching-block, the lower part n^5 and the upper part n^6 of said clenching-block, means of fitting said upper part to said lower part and means of adjusting said upper part, substantially as described and for the reasons set forth.

17. In a box-forming machine in combination, a forming-head, a forming-block, a clenching-block mounted on the auxiliary frame B, a magazine for bottom blanks mounted on the auxiliary frame C, the auxiliary frames B and C and means of adjusting said auxiliary frames, substantially as described.

18. In a box-forming machine in combination, a forming-head, a forming-block, a clenching-block mounted on the auxiliary frame B, the auxiliary frame B, a magazine for bottom blanks, mounted on the auxiliary

frame C, the auxiliary frame C, the screws B', and means of adjusting the frames B, and C, by means of the screws B', substantially as described and for the reasons set forth.

19. In a box-forming machine in combination, a forming-head, a clenching-block, a forming-block, removable face-plates to said forming-block whereby face-plates of different sizes may be interchanged, substantially as described.

20. In a box-forming machine in combination, a forming-head, a clenching-block, a forming-block, a forming-block frame, and means of attaching the forming-block to the forming-block frame so as to secure the circular or tilting adjustment of the forming-block, substantially as described.

21. In a box-forming machine in combination, a magazine for side blanks, a magazine for bottom blanks, a plunger for feeding side blanks, a plunger for feeding bottom blanks, a clenching-block, a forming-block, a forming-head, the forming-clapper frames of said forming-head and the forming-clappers thereof, substantially as described.

22. In a box-forming machine in combination, magazines for side and bottom blanks, plungers for placing the side and bottom blanks in position, a clenching-block, a forming-block, a forming-head, the forming-clappers and forming-clapper frames of said forming-head, and the screws for adjusting said forming-clapper frames, substantially as described.

23. In a box-forming machine in combination, a forming-block, a clenching-block, a forming-head, and means of tilting the side walls of the inverted-V-shaped recess k^2 , of said forming-head without altering the position of the apex of said inverted-V-shaped recess, substantially as described and for the reason set forth.

24. In a box-forming machine in combination a forming-head, a forming-block, a clenching-block, a magazine and a plunger for side blanks, a magazine and a plunger for bottom blanks, and a box-extractor, substantially as described.

25. In a box-extractor of a box-forming machine in combination with a folding mechanism, the forming-block frame, the hinged support the extending arms, the cord and the spring, substantially as described.

26. In a box-extractor of a box-forming machine in combination with folding mechanism a forming-block frame, a hinged support, the extending arms, the cords, the spring, the trip at the rear of the plunger J and the plunger J, substantially as described.

27. In combination in a box-forming machine a forming-head, a forming-block, a clenching-block, a magazine for bottom blanks, a plunger for conveying bottom blanks to the forming-block, and a bottom support for retaining the bottom blanks against the forming-block while the box is being formed, substantially as described.

28. In combination in a box-forming machine, a forming - head, a forming - block, a clenching - block, a magazine for bottom blanks, a plunger for conveying bottom blanks to the forming-block, a bottom support for retaining bottom blanks against the forming-block while the box is being formed and means of reciprocating said bottom support, substantially as described.
29. In a box-forming machine, in combination with a forming-head, a forming-block, a clenching-block, a magazine for side blanks, mechanism for feeding side blanks, a tank for the reception of glue or other adhesive material, a shaft extending longitudinally and journaled in appropriate bearings in said tank and brushes upon said shaft which apply glue or other adhesive material to the side blanks, substantially as described and for the reasons set forth.
30. In a box-forming machine, in combination, a forming - head, a forming - block, a clenching-block, a magazine and feeding mechanism for side blanks, a tank for the reception of glue or other adhesive material, a shaft penetrating one end and extending longitudinally to the other end of said tank, proper bearings for said shaft, brushes which apply glue to the said blanks, means of fitting said brushes to said shaft, and means of adjusting said brushes on said shaft, substantially as described and for the reasons set forth.
31. In a box-forming machine, in combination, a forming - head, a forming - block, a clenching - block, a magazine and feeding mechanism for side blanks, a tank, a shaft journaled to revolve in said tank, brush-wheels on said shaft, and means of fixing at proper intervals in said wheels brushes, which apply glue to the side blanks, substantially as described and for the reasons set forth.
32. In a box-forming machine, in combination, a forming - head, a forming - block, a clenching - block, a magazine and feeding mechanism for side blanks, a tank for the reception of glue or other adhesive material, a shaft which penetrates said tank, appropriate bearings for said shaft, brushes which apply glue or other adhesive material to the side blanks, means of attaching said brushes to said shaft, means of spacing brushes longitudinally on said shaft, and means of spacing brushes at intervals around said shaft, and means of revolving said shaft, substantially as described and for reasons set forth.
33. In a box-forming machine in combination, a magazine for side blanks, a bottom
- plate for said magazine, openings in said bottom plate for the passage of glue-brushes, a tank for the reception of glue or other adhesive material, a shaft in said tank and brushes on said shaft, substantially as described.
34. In a box-forming machine in combination, a magazine for side blanks, a bottom plate for said magazine, openings in said bottom plate, means of adjusting said openings a tank for the reception of glue or other adhesive material and means of applying said adhesive material in the V-grooves and locking corner grooves of the side blanks, substantially as described.
35. In a box-forming machine, in combination, a forming - head, a forming - block, a clenching - block, a magazine and feeding mechanism for side blanks, a tank for the reception of glue or other adhesive material, means of applying adhesive material to the side blanks, and means of heating said adhesive material, substantially as described.
36. In a box-forming machine, in combination, a forming - head, a forming - block, a clenching - block, a magazine and feeding mechanism for side blanks, the end stop of said magazine, means of adjusting said end stop, a tank for the reception of glue or other adhesive material and means of applying said adhesive material to the side blanks, substantially as described.
37. In a box-forming machine in combination with a forming-head, a forming-block, a clenching-block, a plunger for side blanks, a flange-like projection from the bottom of said plunger, and the guiding-groove in A², substantially as described and for the reason set forth.
38. In a box-forming machine in combination with a forming-head, a forming-block, a clenching-block, a magazine for side blanks, a plunger for side blanks, and the reciprocating mechanism thereof, substantially as described.
39. In a box-forming machine in combination with a forming-head, a forming-block, a clenching-block, a magazine for side blanks, a plunger for side blanks, and the means of adjusting the throw of said plunger, substantially as described.
- In testimony that I claim the foregoing as my own I have hereto affixed my signature in the presence of two witnesses.
- HENRY STEWART.
- Witnesses:
- GEORGE R. SHAW,
C. J. WARNER.
